CLAIM

The ornamental design for a RFID tag, as shown and
described.

DESCRIPTION

FIG. 1 is a perspective view of a RFID tag, as shown.

FIG. 2 is a front view of the RFID tag thereof;

FIG. 3 is a rear view of the RFID tag thereof;

FIG. 4 is a left side view of the RFID tag thereof;

FIG. 5 is a right side view of the RFID tag thereof;

FIG. 6 is a top view of the RFID tag thereof; and,

FIG. 7 is a bottom view of the RFID tag thereof.

The broken lines depict portions of the RFID tag that form
no part of the claimed design.

1 Claim, 7 Drawing Sheets
